CLAIM

The ornamental design for a package with surface ornamentation, as shown and described.

DESCRIPTION

FIG. 1 is a front elevational view of a package with surface ornamentation;

FIG. 2 is a front elevational view showing the package with surface ornamentation of FIG. 1 in an alternative unclaimed environment;

FIG. 3 is a front elevational view showing the package with surface ornamentation of FIG. 1 in a second alternative unclaimed environment; and,

FIG. 4 is a front elevational view showing the package with surface ornamentation of FIG. 1 in a third alternative unclaimed environment.

The broken lines showing the package are included for the purpose of illustrating environmental structure and form no part of the claimed design. The claim is limited to the solid lines in the drawings.
